[57] CLAIM

The design for a support for a water sprinkler, as shown and described.

DESCRIPTION

FIG. 1 is a front elevational view of a support for a water sprinkler in accordance with my new design;

FIG. 2 is a rear elevational view thereof;

FIG. 3 is a right side elevational view thereof;

FIG. 4 is a left side elevational view thereof;

FIG. 5 is a top view of the support of FIG. 1; and,

FIG. 6 is a bottom view of FIG. 1.

FIG. 2Fig. 3FIG. 4FIG. 5

FIG. 6
